DESIGN FOR A ROCKING HORSE

Arthur C. De Vorn, Cleveland Heights, Ohio

Application July 6, 1945, Serial No. 120,544

Term of patent 3½ years

(Cl. D34—15)

To all whom it may concern:

Be it known that I, Arthur C. De Vorn, a citizen of the United States and a resident of Cleveland Heights, in the county of Cuyahoga and State of Ohio, have invented a new, original, and ornamental Design for a Rocking Horse, of which the following is a specification, reference being had to the accompanying drawing, forming a part thereof.

In said drawing:

Fig. 1 is a side perspective view of a rocking horse, showing my new design; and Fig. 2 is a perspective longitudinal sectional view of said rocking horse. In said views, the dominant features of the design are shown in full lines.

I claim:

The ornamental design for a rocking horse, as shown and described.

ARTHUR C. DE VORN.
